CLAIM

The ornamental design for a wall sconce, as shown and described.

DESCRIPTION

FIG. 1 is a perspective view of a wall sconce comprising the new design showing the first embodiment, configured with a crystal bobeche shown in dashed lines;

FIG. 2 is a front elevational view thereof;

FIG. 3 is a right side elevational view thereof, a left side elevational view being a mirror image thereof;

FIG. 4 is bottom view thereof;

FIG. 5 is a perspective view of the wall sconce showing the second embodiment, configured with a plain bobeche shown in dashed lines.

FIG. 6 is a front elevational view thereof;

FIG. 7 is a right side elevational view thereof, a left side elevational view being a mirror image thereof; and,

FIG. 8 is a bottom view thereof.

The broken lines in the figures are for illustration purposes only and form no part of the claimed invention.
